MARQUEE LETTER CONVEYOR

Harry W. Moreland, Jr., Portsmouth, Va., assignor
of one-third to Richard F. Smith and one-third
to Albert H. Stockmar, both of Douglassville, Ga.

Application October 28, 1944, Serial No. 560,870

3 Claims. (Cl. 294—19)

1

The present invention relates generally to portable lifting devices and more particularly to a pole-supported elevating means for conveying the letters used in theater marquee signs to and from their proper positions to effect the changing of such signs.

It is the current practice when changing the sign advertising of a particular picture at a theater to make use of a high step ladder which must be climbed in order to make the change of letters and obviously entails frequent moving of the position of the ladder and mounting and dismounting from the same. This current practice is highly dangerous, not only to the operator because of possible serious falls from the ladder and risk to the sign letter equipment, but also to the passing public.

The present invention has for its chief object the elimination of the above dangers and inconveniences by providing an improved portable, manually operated device for elevating the letters to be used to their particular place in the sign.

It is another important object of the present invention to provide a portable, manually operated lifting device for theater marquee sign letters which will readily clasp and elevate such letters to proper position at which point they may be as readily released to rest upon the usual supporting bars or cables of the sign.

It is a further object of the invention to provide a portable manually operated lifting device for letters to be used in theater marquee signs which is adjustable for various sizes of letters which may be released in the proper position or picked up therefrom by an operator on the ground.

Other objects and advantages of the present invention will become apparent during the course of the following description.

In the drawings I have shown three embodiments of the present invention.

In these drawings:

Figure 1 is a side elevation of the apparatus comprising the present invention and showing it in operative relation with respect to a theater marquee sign;

Figure 2 is a side elevation partly broken away and partly in cross-section of the hand reel for elevating and lowering the letters supporting carriage;

Figure 3 is a horizontal section taken on line 3—3 of Figure 2;

Figure 4 is a horizontal section taken on the line 4—4 of Figure 2;

Figure 5 is a horizontal section taken on the line 5—5 of Figure 2;

2

Figure 6 is a view in side elevation, partly in section, to an enlarged scale, of the letter clamping carriage and the upper end of the supporting post;

5 Figure 7 is a horizontal section taken on the line 7—7 of Figure 6;

Figure 8 is a horizontal section taken on the line 8—8 of Figure 6;

10 Figure 9 is a vertical section taken on the line 9—9 of Figure 6;

Figure 10 is a horizontal section taken on the line 10—10 of Figure 6;

15 Figure 11 is a view in elevation, partly in section, of a modification of the present invention; and

Figure 12 is a view in elevation, partly in section, of a further modification of the present invention.

Referring now to the drawings, numeral 20 designates as a whole a supporting pole upon which a letter-clamping carriage 22 is slidably mounted in parallel, longitudinally extending slots 24 for vertical movement by means of a hand reel 26.

25 The pole 20 is formed in two longitudinally extending sections 30 and 32 which are secured together by means of suitable screws throughout their length. The hand reel 26 comprises a pulley 34 having a deep annular flexible cable-

30 receiving groove 36 in its outer periphery and is keyed to a shaft 38 and provided with a suitable crank 40. The upper end of the pole 20 is provided with a small pulley 42 suitably journaled therein and a flexible cable 44 connected

35 at one end to the base of the carriage 22, passes over the pulley 42, through a slot 46 formed in the inner face of pole section 32, and over the reel 34 to which the other end is secured. The post 24 is provided with an additional pair of

40 longitudinally extending slots 48 and 50 formed in the inner faces of the sections 30 and 32 to also receive flexible cables 52 and 54 as will be described, and with a longitudinally extending slot 49 formed in the front face of the pole.

45 The inner face of section 30 is slotted as at 50 to receive a catch member 60 pivoted at 62 and provided with a lug 64 to which is secured the upper end of the cable 54 (Figure 6), the lower end of the cable being attached to a trigger 66 pivoted as at 68 within a slot 70 formed

55 in the section 32 (Figures 2 and 3). It will be apparent that movement of the trigger upwardly or counterclockwise will depress the other end of the trigger 66 to put a downward pull on the cable 54 to effect a clockwise rotation of catch 60 about its pivot 62 against the action of

a compression spring 70 to withdraw the outer edge of the catch within the front surface of the hole 20. A supporting catch or stop is thus provided for the carriage 22 when raised to its uppermost position as shown in Figures 1 and 6, thus relieving tension on the flexible cable 44.

An actuating trigger 72 is pivotally mounted as at 74 in a slot 76 provided in the upper end of the pole 20 and is provided with a pair of finger portions 78 and 80. The upper end of the cable 52 is connected to the finger 78 and passes downwardly through the longitudinally extending slot 48 to be secured to the end 82 of an operating lever 84 which is pivotally mounted as at 86 within a slot 88 formed in the pole adjacent the reel 26. Depression of the operating lever 84 effects a downward pull on the finger 78 causing the finger 80 to move in a counterclockwise direction about its pivot 74 to engage the upturned flange 90 of an actuating member 92 which extends forwardly through a slot 93 in the base of the carriage 22 and is slidable vertically in the slot 49. Release of pressure upon the actuating lever 84 causes the trigger 72 to return to the position shown in Figure 6 under the action of a tension spring 94.

The cable 44 which effects the elevation of the carriage 22 as well as the catch operating cable 54 and jaw operating cable 52, may be of heavy woven cord, flexible link cable, or even spring steel banding of the type used for measuring tapes.

The carriage 22 comprises a bracket 96 including a base 98 having four leg portions which are bent in the form of a channel (Figure 3), the flange portions of which are again bent and received within the longitudinally extending slots 24 provided in the side surfaces of sections 30 and 32 of the pole 20. The flange portions 100 of the base 98 have an easy sliding fit in the slots 24 so that motion of the carriage with respect to the pole may be easily effected by the hand reel 26.

The carriage 22 further comprises a pair of adjustable jaws 102 and 104 having shoulders 103 and which are connected by a U-shaped metal strap 106 having an inturned flange 107 which is pivotally mounted on the bracket 96 as at 108. Depending from an eyestrap in the lower leg of the U-shaped member 106 is a stub shaft 110 provided in its front surface with a longitudinally extending guiding groove 112, also with a plurality of spaced transverse notches 114 for a purpose which will be described. The lower carriage jaw 104 is slidably mounted on the shaft 110 and is provided with a vertical flange 116 which tracks in the slot 112. The jaw is retained in the adjusted vertical position by means of a horizontally pivoted lever 118 which is provided at its opposite end with a flat lugged portion 120 which cooperates with any one of the transverse notches 114. The upper leg of the U-shaped member 106 has a stub shaft 122 extending upwardly therefrom and having in its front face a longitudinally extending slot portion 124 in which an upstanding flange 126 mounted on the jaw 102 tracks or slides. A stud 128 projects through the front side of the shaft 122 and into a longitudinally extending slot 130 in which is arranged a compression spring 130' which acts downwardly on the flange 126 to provide the resilient clamping action of the jaws 102 and 104.

The flange 126 on upper jaw 102 is slidably mounted in the hollow shaft 122 and is in engagement with a thrust pin 132 which is ar-

ranged for vertical movement in shaft 122 and along a fixed guide member 134. The inturned flange 107 of the U-shaped member 106 is provided with a V-shaped angle member 136 which receives and guides a roller 138 mounted on the lower end of bar 140 which is pivotally connected to the lower end of the member 132. The bar 140 is connected intermediate its ends to the lever 92 by means of a crank member 142, the lever 92 being guided in its horizontal reciprocation to be described by a notched lug 144 fixed to the bracket 96.

In Figure 11 I have disclosed a modified form of the article-supporting carriage in which the adjustable clamping jaws 102 and 104 have been omitted and a pair of vacuum cups 146 substituted therefor which are mounted on a plate 148 having an inturned flange 150 which is pivotally connected to the bracket 96. The vacuum cups 146 are connected by a pair of rubber hoses 152 to a vacuum release valve 154 which is operated by levers 142 and 92 to release the vacuum when it is desired to release the letters supported by vacuum cups.

In Figure 12 I have shown a further modification of the letter supporting portion of the carriage wherein a pair of electromagnets 154 are provided in the face of a plate 156 which is attached to the flange member 150 and pivotally mounted to the bracket 156 as before. In such case each of the letters 164 forming the sign on the theater marquee are provided with metal buttons 158 suitably placed in the body of the letter so as to be affected by the magnetic attraction of the magnets 154 of the letter supporting plate 156. A switch box 160 may also be mounted on the flange 150 and connected by levers 142 and 92 with the actuating trigger 72 as shown in Figure 6. It will be apparent that actuation of the trigger 72 will move levers 142 and 92 to the right to throw the switch 162 to open the circuit between a battery (not shown) suitably mounted on the pole 20 and the electromagnets 154 to release the letters 164 supported by the magnets 154.

As seen in Figure 1, a letter 164 supported by the carriage 22 is about to be placed on the parallel horizontally extending wire or bar supports 172 of a theater marquee sign 174. The side flanges at the back of each letter are provided with two pairs of inwardly and upwardly inclined slots 176 within which the parallel rods 172 are adapted to be received to support the various letters in their respective positions on the sign.

The operation of the apparatus will now be described.

The operator grasps the pole 20 in his left hand just about the reel 26 so that his left thumb may operate either of the levers 66 or 84. The proper letter to be placed upon the marquee sign is selected with his right hand and placed between the jaws 102 and 104 of the carriage 22 as the operator's left thumb depresses trigger 84 to open them. Thumb pressure is then released and the letter is securely held between the jaws.

The carriage 22 is now elevated to the top of the pole 20 by turning the crank 40 in a counterclockwise manner with the right hand, and when the base of the carriage 98 passes over the catch 60 it depresses the same against the action of the compression spring 70. Upon passage of the sliding base 98, the catch again projects outwardly of the slot 58 and as the carriage is now substantially at its upper limits of movement, mo-

tion of the crank is stopped and the carriage is permitted to rest upon the catch 60.

The operator now positions the letter 164 with respect to the supporting bars 172 and inserts the slots 176 of the letter thereover, the carriage being pivotally mounted as at 108 with respect to the bracket 96. When the letter is properly placed, the operator depresses the actuating lever 84 which causes counterclockwise rotation of trigger 72 to urge the lever 92 inwardly or to the right as shown in Figure 6. The wheeled lever 140 is now moved to the right by virtue of its connection therewith and contact of the wheel 138 with the V-shaped guide 136 forces member 132 upwardly by virtue of its pivoted connection with member 140. This upward movement of member 132 along the sliding guide 134 moves the upper jaw 102 upwardly against the action of compression spring 130' to release the letter 164. Thumb pressure on lever 84 is then released. It will be appreciated that the jaws are pivotable with respect to the pole so that even though the letter is necessarily held at an angle by a compression spring 109 the letter will be substantially parallel to the sign. The jaws, of course, are operable at all angles of adjustment thereof relative to the pole.

The operator may now position the still elevated carriage 22 adjacent a letter which is to be removed from the supporting bars 172 of the marquee sign 174 and the lever 84 again depressed to open the jaws 102 and 104 about the letter and thumb pressure released to clamp the jaws upon its upper and lower edges. The carriage pole is withdrawn from the immediate vicinity of the sign and the operator's right hand again placed on the crank ready to retard the downward descent by gravity of the carriage 22. The left thumb of the operator now depresses trigger 66 to withdraw catch 60 from beneath the sliding base 98 of the carriage which then descends by gravity resisted and controlled by the operator's right hand on the crank 40. Upon arrival of the carriage at the lower limits of the supporting and guiding slots 24 adjacent the operator's left hand, the operator may then remove the letter from the jaws 102 and 104 while simultaneously depressing trigger 66 to open them.

The operation of the embodiment disclosed in Figure 11 is substantially the same as before described. While the operator holds the pole 20 in his left hand as described, a letter 164 is pressed against the vacuum cups 146 which will support the same and the carriage is then elevated to the upper end of the rod. When the letter is properly positioned with respect to the supporting rods 172, the lever 84 is depressed by the operator's left thumb to move the trigger 72 to effect inward movement of the lever 92 which operates the vacuum release valve 150 to release the letter 170 in its proper position. Obviously, letters may be removed from the sign by pressing the vacuum cups thereagainst while the carriage is in its elevated position on the post 20.

The operation of the embodiment disclosed in Figure 12 is also substantially similar to the operation of the first two embodiments. The pole 20 is held by the left hand adjacent the trigger 66 and the lever 84 and the letter 164 placed so that the metallic buttons 168 are adjacent the electromagnets 164 to be supported thereby. The carriage is then elevated to the upper limits of the pole and again placed in proper position with respect to the supporting rods 172 of the marquee

sign. The lever 84 is then depressed to again effect movement of the lever 96 inwardly to open the switch 162 rendering the electromagnets ineffective and releasing the letter 164 in its proper position upon the rods 172.

It will now be obvious that the present invention is simply though ruggedly constructed, capable of wide adjustments for letters of various sizes and arranged to be operated in a natural fashion without difficulty.

Although the present invention has been described in its application for theater marquee letters, it will be readily apparent that other articles may be raised or lowered to or from various positions thereby with only slight variations in the shape of the holding means to accommodate the same.

It is to be understood that the forms of the invention herein shown and described are to be taken as preferred examples of the same and that varying changes in the shape, size and arrangement of parts may be resorted to without departing from the spirit of the invention or scope of the subjoined claims.

I claim:

1. A device for conveying articles to an elevated position comprising a pole, a bracket slidably mounted on said pole, article-holding means pivotally mounted on said bracket, and means associated with said pole for elevating said holding means, said holding means comprising a support, a pair of oppositely projecting stub posts mounted thereon, and a pair of clamping jaws adjustably mounted on said posts.

2. A device for conveying articles to an elevated position comprising a pole, a bracket slidably mounted on said pole, article-holding means pivotally mounted on said bracket, and means associated with said pole for elevating said holding means, said holding means comprising a support, a pair of oppositely projecting stub posts fixed thereto, a pair of clamping jaws adjustably mounted on said posts, one of said posts including spaced transverse slots therein, and a lever pivoted to one of said jaws and engageable with one of said slots to retain said jaw in adjusted position on said post.

3. A device for conveying articles to an elevated position comprising a pole, a bracket slidably mounted on said pole, article-holding means pivotally mounted on said bracket, and means associated with said pole for elevating said holding means, said holding means comprising a support, a pair of oppositely projecting stub posts fixed thereto, and a pair of clamping jaws adjustably mounted on said posts, one of said posts being provided with spring means to urge one of said jaws to article-holding position.

HARRY W. MORELAND, JR.
